CHIPPER KNIFE FOR USE IN A WOOD CHIPPING MACHINE

James R. Ross, Cookeville, Tenn., assignor to Vistron Corporation, Cleveland, Ohio

Filed June 14, 1973, Ser. No. 369,998

Term of patent 14 years

Int. Cl. D15—99

U.S. Cl. D8—90

FIG. 1

FIG. 2

FIG. 3

FIG. 4

FIG. 5

FIG. 1 is a perspective view of a chipper knife for use in a wood chipping machine showing my design;

FIG. 2 is a top plan view;

FIG. 3 is a view taken on line 3—3 in FIG. 2;

FIG. 4 is an elevational view taken on line 4—4 in FIG. 3; and

FIG. 5 is an elevational view taken on line 5—5 in FIG. 3.

I claim:

The ornamental design for a chipper knife for use in a wood chipping machine, as shown.
